WATCH VISE

William D. Pyle, Indianapolis, Ind., assignor of one-half to Emery C. Tharp, Indianapolis, Ind.

Application December 16, 1954, Serial No. 475,757

4 Claims. (Cl. 81—6)

This invention relates to a vise, particularly adapted for use by watchmakers, and in particular, a base having a stationary jaw with spaced openings therein extended upwardly from one end, a coacting jaw movably mounted by a stock on the base and also having spaced openings therein with means for clamping the movable jaw through the stock thereof to the base and with a thumb screw and disc combination for forcing a watch assembly from a case, particularly of the waterproof type.

The purpose of this invention is to provide a relatively small vise for holding a watch case as the back of the watch is removed therefrom and which is also adapted to hold the watch case as the interior of the watch is forced therefrom and replaced therein.

Because of the relatively thin material of a watch case, it is difficult to positively grip and hold a case as a back is unscrewed or removed therefrom without distorting the case and, with a watch case slightly distorted, it is substantially impossible to replace a back or the interior assembly of the watch. With this thought in mind, this invention contemplates a vise for gripping and holding a watch case wherein both a stationary jaw and a movable jaw of the vise are provided with spaced openings positioned to receive ears extended from a watch case, such as a case of a wrist watch and wherein with the ears extended into the openings of the jaws the case is adapted to be rigidly held as the back thereof is removed and as the interior assembly is removed and replaced.

The object of this invention is, therefore, to provide a vise for holding a watch case as the back is removed and replaced in which the case is rigidly held without danger of distortion therein.

Another object of the invention is to provide a vise for holding a watch case in which the vise is readily adjustable to correspond with watch cases of different types.

Another important object of the invention is to provide a vise for gripping a watch case in which means is provided for forcing the interior of a watch from and into a case.

A further object of the invention is to provide a watch case gripping vise in which the vise is of a simple and economical construction.

With these and other objects and advantages in view, the invention embodies an elongated plate providing a base with one end extended upwardly forming a stationary jaw, a stock having an elongated slot therein positioned on the base and having an end extended upwardly to provide a movable jaw, a pivot pin extended through the slot of the stock of the movable jaw and being secured in the base of the stationary jaw, a stud secured in the base of the stationary jaw, also extended through the slot of the stock of the movable jaw, and having a thumb nut thereon, and a thumb screw threaded in a bushing in the base of the stationary jaw and having a disc on the extended end, the disc being positioned to register with the interior of a watch case

2

clamped between the movable and stationary jaws of the vise.

Other features and advantages of the invention will appear from the following description, taken in connection with the drawing, wherein:

Figure 1 is a side elevational view of the improved watch vise with the movable jaw of the vise shown in one position in full lines and in another position in dotted lines and with a watch positioned between the jaws also shown in dotted lines.

Figure 2 is a plan view of the vise as shown in Figure 1 also showing a watch clamped between a movable and a stationary jaw of the vise with the watch shown in dotted lines and also showing the movable jaw in one position in full lines and in another position in dotted lines.

Figure 3 is a longitudinal section through the vise taken on line 3—3 of Figure 2, the illustration of the watch case being omitted.

Figure 4 is a cross section through the vise taken on line 4—4 of Figure 1 showing the stationary jaw on one end of the base of the vise.

Referring now to the drawing, wherein like reference characters denote corresponding parts, the improved watch vise of this invention includes a base 10 having a stationary jaw 11 extended upwardly from one end, a stock 12 having a movable jaw 13 extended upward from one end, the jaw 13 being positioned to coact with the stationary jaw 11, a pivot pin 14 extended through a slot 15 in the stock 12 and having an enlarged head 16, a threaded stud 17 threaded into the base 10 and also extended through the slot 15, a thumb nut 18 positioned on the stud 17 and having a washer 19 adapted to straddle the slot 15, and a thumb screw 20 having a knurled head 21 on one end and a disc 22 on the opposite end threaded in a bushing 23 mounted, such as by a press fit, in an opening 24 in the base 10 and positioned whereby the disc 22 is between the stationary jaw 11 and the movable jaw 13.

As illustrated in Figure 4, the stationary jaw 11 is provided with spaced openings 25 and 26 that are positioned to receive ears 27 and 28, respectively, of a watch case 29 and the jaw 13 is provided with similar openings 30 and 31 that are positioned to receive corresponding ears 32 and 33, respectively, on the opposite side of the watch case, the watch case and ears being shown in broken lines.

One side 34 of the stock 12 of the movable jaw is provided with an arcuate surface 35 whereby the jaw 13 with the stock upon which the jaw is mounted are adapted to be rotated in a clockwise direction about the pivot pin 14 to open the jaws to facilitate inserting watch cases in the jaws and also to facilitate removing watch cases from the vise.

Because of the very small size of the wrist band connecting ears on opposite sides of a watch case it is difficult to insert the four ears at the same time and for this reason the extended end of one of the sections of the stock 12 is cut away providing an arcuate surface 35 which is adapted to slide against the threaded stud 17 to permit rotating the stock 12 about the pivot pin 14 so that the jaw 13 may be opened to a slight angle to permit the ears 27, 28, and 33 being inserted in the notches or slots and with these ears in the notches the stock 12 is turned back to the position shown in Fig. 2 whereby the ear 32 may enter the slot 30.

The disc 22 is provided with a concave upper surface, as indicated by the numeral 36, to facilitate engagement thereof with the interior assembly of the watch.

With the parts formed in this manner, the watch vise is readily adjusted to watch cases of different sizes and

with a watch case gripped between the jaws, as illustrated in Figures 1 and 2, the back may readily be removed therefrom and may also be readily replaced on the watch case.

By removing both the front and back of the watch case, the works or inner assembly of the watch may be removed by forcing the disc 22 upwardly by the thumb screw 20 and by the same means the interior assembly may be pressed into the watch case.

Operation

The watch vise of this invention is positioned upon a watchmaker's work bench and with the jaw 13 moved away from the jaw 11 a watch case is positioned between the jaws with the ears 27 and 28 extended into the openings 26 and 25 respectively and as the jaw 13 is returned to the position shown in Figs. 1 and 2 the ears on the opposite side of the watch case are inserted in the openings or recesses 30 and 31 and the stock 12 is then moved toward the end of the vise in which the watch case is positioned and the watch case is secured in position in the vise by tightening the thumb nut 18. With the watch case firmly clamped between the jaws 11 and 13 both the face and back are adapted to be rotated in counter-clockwise direction whereby these parts may be readily removed. With the front and back of the watch case removed the threaded stud 20 is rotated by the knurled head 21 whereby the disc 22 forces the clock works assembly from the case.

It will be understood that modifications, within the scope of the appended claims, may be made in the design and arrangement of the parts without departing from the spirit of the invention.

What is claimed is:

1. A watch vise comprising an elongated base having a stationary jaw extended upwardly from one end, a movable jaw having a stock with an elongated slot therein slidably mounted on the base and positioned to coact with the stationary jaw, a pin mounted in the base and extended through the slot of the movable jaw, a threaded stud threaded in the base and also extended through the slot of the movable jaw, a thumb nut threaded on said stud, said jaws having spaced aligned openings therein, a thumb screw threaded in the base and positioned between the jaws, and a watch case retaining disc positioned on the upper end of the thumb screw.

2. In a watch vise, a combination which comprises an elongated base having a stationary jaw with spaced openings therein extended upwardly from one end, a movable jaw also having spaced openings therein carried by a stock slidably mounted on the base, the openings of the stationary and movable jaws being positioned to receive the wrist band mounting ears of a watch case, said mov-

able jaw being positioned to coact with the stationary jaw, said stock of the movable jaw having a longitudinally disposed slot therein, a pin extended from the base through the slot of the movable jaw, a threaded stud extended from the base through the slot of the movable jaw, and a wing nut threaded on said threaded stud for clamping the movable jaw in position for retaining a watch case between the jaws.

3. In a watch vise, a combination which comprises an elongated base having a stationary jaw with spaced openings therein extended upwardly from one end, a movable jaw also having spaced openings therein carried by a stock slidably mounted on the base, the openings of the stationary and movable jaws being positioned to receive the wrist band mounting ears of a watch case, said movable jaw being positioned to coact with the stationary jaw, said stock of the movable jaw having a longitudinally disposed slot therein, a pin extended from the base through the slot of the movable jaw, a threaded stud extended from the base through the slot of the movable jaw, a wing nut threaded on said threaded stud, and a thumb screw having a disc on the inner end threaded in the base and positioned between the movable and stationary jaws.

4. In a watch vise, a combination which comprises an elongated base having a stationary jaw with spaced openings therein extended upwardly from one end, a movable jaw also having spaced openings therein carried by a stock slidably mounted on the base, the openings of the stationary and movable jaws being positioned to receive the wrist band mounting ears of a watch case, said movable jaw being positioned to coact with the stationary jaw, said stock of the movable jaw having a longitudinally disposed slot therein, a pin extended from the base through the slot of the movable jaw, a threaded stud extended from the base through the slot of the movable jaw, a wing nut threaded on said threaded stud, and a thumb screw having a disc on the inner end threaded in the base and positioned between the movable and stationary jaws, the stock of said movable jaw having an arcuate surface on one side to facilitate turning the movable jaw on the base.
